UNITED STATES PATENT OFFICE.

ALBERT F. LESLER, OF NEW YORK, N. Y.

PAPER DISPENSER.

Application filed June 21, 1922. Serial No. 569,786.

To all whom it may concern:

Be it known that I, ALBERT F. LESLER, a citizen of the United States, and a resident of the city of New York, borough of 5 Manhattan, in the county and State of New York, have invented new and Improved Paper Dispensers, of which the following is a full, clear, and exact description.

This invention relates to paper dispensers 10 and particularly to an improved dispenser for protecting toilet paper and has for an object the provision of a simple but very effective holder adapted to dispense one sheet of paper at a time.

15 Another object of the invention is to provide a dispensing device for toilet paper which will ordinarily protect the paper but which will not allow the paper to be removed by a direct pull, the arrangement being such that the supporting members will act as cutters as the paper is removed.

A still further object of the invention is to provide a dispensing device for toilet paper which will prevent the paper from 25 becoming tangled as the sheets are successively removed.

In the accompanying drawing—

Figure 1 is a plan view with certain parts broken away disclosing one embodiment of the invention.

Figure 2 is a sectional view through Figure 1 on line 2—2, the same being on a greatly enlarged scale.

Figure 3 is a transverse sectional view 35 through Figure 1 on line 3—3.

Figure 4 is an enlarged perspective view of one of the supporting brackets shown in Figure 1.

Figure 5 is a sectional view similar to 40 Figure 2 but showing the modified form of the invention.

Referring to the accompanying drawings by numerals 1 indicates a casing which is sealed or closed tightly throughout except 45 at the bottom which is open and which is provided with cut away portions or notches 2 and 3 whereby the thumbs of an operator may readily press the top sheet of paper 4 and pull the same outwardly without molesting 50 the remaining sheets 5. The various sheets 4 and 5 and casing 1 are supported on a pair of brackets or clips 6 constructed as shown particularly in Figure 4. These brackets are provided with a body portion 55 merging into an apertured extension 8 designed to receive a nail or other support and

into a supporting cutting member 9 which in turn merges into a turned over clamping ear 10. The supporting cutting member 9 extends through the back of the casing and through the package of paper as shown in Figure 1 and is then bent over for forming the clamping ear 10 at the front part of the package. In this way, the paper is supported on the edge of the cutting member 9, 60 which cutting member will properly support the paper until some appreciable pull is exerted on the paper whereupon the paper will move downwardly and become cut as shown in Figure 1.

As the paper cannot be grasped except by the thumbs, the pressure is naturally against the paper and then in a downward direction whereby only the top sheet 4 will be removed as the downward pressure acts principally 75 on the first sheet and causes it to be readily cut by the members 9. In addition to the arrangement of the members 6, a retaining flap or tongue 11 is provided which is secured by adhesive or other means to the back of casing 1 and extends through the opening 12 of the pad of paper 5 so as to bear upon the protecting extensions 13 forming part of the various sheets. The tongue 11 will not in any way interfere with the removal 80 of any of the sheets of pad 5 but will prevent falling or tangling of the various sheets in the extensions 13.

In Figure 5, a slightly modified construction is shown in which the bottom of the casing 1 is closed by a suitable closing section 32 so that there is only a very small outlet or discharge opening 32'. In addition to this feature, a board or stiff sheet 35 is hinged or otherwise suitably secured at 34 to the back of casing 1, said sheet being forced 90 forwardly by a suitable spring 35 whereby the sheets of paper 5 are held against the front of the casing 1 and may be readily drawn through the opening 32' one at a time. In this form of the invention, the tongue 11 is connected with the sheet 33 instead of the back of the casing.

What I claim is:—

1. In a paper dispensing device of the character described, a casing for receiving a quantity of paper, said casing being open at the lower end and provided with notches at the lower end whereby the thumbs of an operator may engage said paper and remove the same, said paper being formed with a central aperture, and a guiding and retain-

ing tongue secured to the back of said casing and extending through said aperture so as to overlap the top of the paper dispensed and guide the paper as it is moved from the casing.

2. A dispenser for sheets of toilet paper having openings in the center, comprising a casing closed completely except at the bottom, said casing having notches at the bottom so that a person may pass his thumbs through the notches and press against said paper to remove the same through the bottom opening in the casing, a plurality of

brackets acting to support the casing and the sheets of paper therein, each of said brackets having a supporting member and a section extending through said sheets of paper, said section being positioned edgewise to the movement of the paper so that it may be readily torn from said supporting section, and a guiding tongue extending through the opening in said paper, said tongue having one end on one side of the paper dispensed and the other end on the opposite side, one of said ends being secured to said casing.

ALBERT F. LESLER.
